CLAIM

The ornamental design for a carabiner with space for a pinch light, as shown and described.

DESCRIPTION

FIG. 1 is a top plan view of my new design for a carabiner with space for a pinch light, the pinch light shown in dotted lines which is for illustrative purposes only and is not part of the claimed design.

FIG. 2 is a bottom plan view of FIG. 1.

FIG. 3 is a left side elevation view of FIG. 1.

FIG. 4 is a right side elevation view of FIG. 1.

FIG. 5 is a rear side elevation view of FIG. 1.

FIG. 6 is a front side elevation view of FIG. 1; and,

FIG. 7 is a top perspective view of FIG. 1.
